UNITED STATES PATENT OFFICE.

RALPH L. MARTEAU AND GEORGE A. SCHROETER, OF BROOKLYN, NEW YORK.

SHOE CONSTRUCTION.

Application filed December 28, 1925. Serial No. 78,034.

Our invention relates to improvements in shoe construction and has reference particularly to an adjustable metatarsal shoe shank adapted to be incorporated in the ordinary 5 shoe during manufacture thereof for the purpose of affording corrective treatment of the foot in the region of the metatarsal arch.

This invention is a further development of our invention relating to adjustable metatarsal shoe shanks patented December 11, 1923, 10 No. 1,477,146, in which a free flap portion or tongue is arranged in the arch of a shoe, the flap being in the form of a pocket for the purpose of receiving an insert adjustable beneath 15 the anterior metatarsal arch. It will be clear in this connection that while the insert is freely adjustable within the pocket, at the same time such adjustment is indeed limited and by no means allows for extreme cases nor 20 is the insert self-adjustable to accommodate itself to the foot after a shoe has been broken in.

With the foregoing in mind it is the purpose of the present invention to overcome the 25 objectionable features just described and we accomplish this purpose by means of the construction, arrangement and combination of parts hereinafter described and set forth in the appended claims.

30 One embodiment of the invention is illustratively exemplified in the accompanying drawings, in which Figure 1 is a top plan view of the insole of a shoe embodying our invention; Figure 2 is a side view of the same 35 showing the extensible shank portion in section; Figure 3 is a sectional view of the insert and anchoring piece therefor; Figure 4 is a plan view of the insert; Figure 5 is a top plan view of the anchoring piece; and Figure 6 is a side elevational view of the same.

Referring to the drawing and particularly to Figures 1 and 2, 10 denotes the innersole of a shoe, to the under marginal surface of which is attached the welt, or upper and sole 45 not shown, and 11 is the heel section of a shoe shank. The heel section 11 is made of leather having its margin turned downwardly about the edge of the inner sole and between the latter and the welt, or upper and sole. The 50 heel section 11 extends to a point at the beginning of the arch and is attached to one end of a strip of elastic material 12, the opposite end thereof being connected to a free flap section 13 composed of superimposed pieces of leather 55 which are stitched together about their edges but not attached to the insole 10. The two

layers of leather form a pocket which is accessible through a transverse slit 14 cut in the under leather layer.

According to our prior invention an insert 60 of any desired form is arranged in the pocket so as to lend the necessary support to the bones comprising the metatarsal arch of the foot, but it has been found desirable to increase the adjustability of support so that when the 65 shoe has been broken in the position of the insert may be changed.

In the embodiment shown in Figures 3 to 6, we provide a metal anchoring plate 15 having its upper face at a central point adjacent 70 one end provided with an upstanding blunt pin 16; on its under face adjacent opposite sides, and on a transverse line projecting through the central point are disposed two pointed pins 17, which when the plate 15 75 is arranged in the pocket are adapted to project downwardly penetrating the under layer of leather and engaging the inner sole 10.

When arranged in position in the shoe the pin 16 projects upwardly to receive an insert 18 comprising a disc-shaped rubber member provided with an opening 19 to accommodate the pin. The disc 18 is preferably convex curved on its upper surface so as to accommodate itself to the arch and lend 80 as much ease as possible to the wearer. If greater thickness for the insert is required, due to extreme conditions, a washer 20 may be arranged on the pin 16 beneath the disc 18, as illustrated in Figure 3. 85

Our adjustable shank operates as follows: The plate 15 and disc 18 are inserted through the slit 14 into the pocket of the flap 13 as 90 illustrated in Figures 1 and 2. The foot of the wearer is then inserted into the shoe and full weight is brought to bear upon the foot by walking, which enables the arch and foot bones to assume their normal positions. As the weight is placed on the foot the latter rides forward within the shoe and with it the flap 13 and its insert. This is possible because of the elastic connecting piece 12 which gives and enables the insert to find its proper location with respect to the foot of the wearer. The flap having found its correct position, the pins 17 may be pressed into the innersole to 95 fix the position of the disc insert 18. If as the shoe is being worn a change in the position of the insert is required, it is only necessary to lift the flap 13 to release the pins 17 which 100 may be engaged farther forward or rearward of the innersole 10. As previously described 105

extreme cases may necessitate the use of a relatively high insert in which case the disc insert 18 is removed from the pin 16 and one or more washers 20 placed over the plate 15 5 and the disc replaced thereover.

The peculiarities and requirements of individual conditions have been fully explained in our prior patent and it is not believed necessary to again go into detail regarding these 10 points, except to state that according to the present invention substantially universal adjustment of the insert is made possible to meet almost any condition arising from abnormal disposition of the bones of the metatarsal 15 arch.

With the lapse of time if a correction be necessary owing to the forward shifting of the foot, suitable adjustment can be made to extend the forward flap due to the elastic 20 character thereof and in such event the pin or corresponding features provide the means for holding the flap in extended position.

What we claim and desire to secure by Letters Patent is:

- 25 1. In an arch supporting member for a shoe, a heel portion secured to the shoe, a forward flap portion disposed under the arch of the foot, an extensible connecting piece between the heel and forward portions, and 30 means insertible in the forward portion to support the anterior metatarsal arch of the foot.
2. In combination, an arch supporting member for the innersole of a shoe comprising

a heel portion secured to the shoe, a forward 35 flap portion under the arch of the foot, an elastic connecting member between the heel and flap portions, said flap having an internal pocket and access thereto through an opening in one face, and a supporting member insertible into said pocket through the opening. 40

3. An arch supporting member, as claimed in claim 2, in which the insertible supporting member comprises a flexible disc, and means for fixing the position of the disc and 45 flap with respect to the heel portion.

4. An arch supporting member, as claimed in claim 2, in which the insertible supporting member comprises a metal plate having oppositely projecting pins, one set of pins being arranged to project through one wall of the pocket and anchor in the innersole, and a removable disc arranged on the other pin and adapted to raise the other wall of the pocket 50 to support the foot. 55

5. An adjustable insert for the pocket of an arch supporting member of the character described, comprising a flat plate provided with a set of pointed pins projecting from one face and a centrally located blunt pin projecting from the other face, and a flexible disc to be superimposed on the plate and having an opening to receive the blunt pin. 60

In testimony whereof they have affixed their signatures.

RALPH L. MARTEAU.
GEORGE A. SCHROETER.
